UNITED STATES PATENT OFFICE.

HAROLD G. WARR, OF PARK RIDGE, ILLINOIS, ASSIGNOR TO THE P & M COMPANY, OF CHICAGO, ILLINOIS, A CORPORATION OF ILLINOIS.

RAIL ANCHOR.

Application filed June 24, 1921. Serial No. 480,004.

To all whom it may concern:

Be it known that I, HAROLD G. WARR, a citizen of the United States, residing at Park Ridge, in the county of Cook and 5 State of Illinois, have invented certain new and useful Improvements in Rail Anchors, of which the following is a specification.

My invention relates to devices for resisting the tendency of railroad rails to creep 10 longitudinally.

The principal object of the invention is to provide an improved anchor device which may be easily applied to a rail and which when applied will maintain a firm engagement 15 with the rail base during the presence of movements of the rail in either direction. In this connection, the invention contemplates the provision of an anchor device comprising a rail embracing yoke member, 20 a tie abutting wedge member adapted to be forced between the rail and the yoke member, and fastening means secured to a tie and adapted to engage with said yoke so as to prevent the yoke backing off the tie abutting 25 wedge member when the rail is subjected to a counter-creeping movement; that is, a movement in a direction away from the tie through the yoke.

The invention consists in the new and improved 30 constructions and combinations of parts, hereinafter more specifically described and claimed, for carrying out the above stated object, and such other incidental objects as will appear from the following description.

In the drawing:

Fig. 1 is a plan view of a rail anchor device constructed in accordance with my invention, applied in its operative position 40 on the base flange of a rail, a portion of the rail being broken away for the purpose of clearness;

Fig. 2 is a side view of the rail anchor shown in Fig. 1, with parts of the device 45 shown in section;

Fig. 3 is a cross-sectional view taken on the line 3—3 of Fig. 1, looking in the direction indicated by the arrows; and

Fig. 4 is a view in perspective of one of 50 the members forming a part of my improved rail anchor device.

Like characters of reference designate corresponding parts in the several figures of the drawing.

55 The invention preferably consists of a

yoke member 10, a tie abutting wedge member 11, and attaching members 12, 12^a. The yoke member 10 is formed at opposite ends with hook-shaped portions providing jaws 13, 14, which engage the upper surfaces of the rail base. The hook-shaped portion of 60 the jaw 14 is made somewhat longer than the jaw portion 13 so as to provide a relatively deep recess 15 adapted to receive one of the base flanges of the rail base and provide 65 sufficient clearance to permit the yoke member to be moved in the direction of its length, so as to hook the jaw 13 over the opposite edge of the rail base. The yoke member preferably has some resiliency and 70 is held in gripping contact with the rail base 16 by means of the wedge member 11 which is forced between the under surface of the rail base and the yoke member 10. The wedge member is formed with a tie-abutting flange 17 and with a longitudinally 75 extending corrugation 18. The corrugation 18 increases in depth toward the tie abutting flange 17 and provides the tapered under surface of the wedge. The yoke member 10 80 is formed near its middle with a recess 20 which provides a curved seat for the corrugation 18 of the wedge member 11. The yoke is held against movement away from the tie by means of fastening members 12, 85 12^a secured to the tie and adapted to engage the rear face of the yoke member. In the drawing I have shown one of such casting members for each side of the rail so as to hold the yoke at right angles to the wedge 90 member. It will be obvious, however, that, in situations where it is not objectionable for the yoke to assume a position diagonally across the rail, or where the specific construction of the yoke member is such as to 95 prevent angular displacement with relation to the wedge, the yoke may be held in a satisfactory position by the use of one of such fastening members. The fastening members 12, 12^a, are made in rights and 100 lefts, and consist in each case of a flat hook-shaped bar bent over at one end to provide a rail base engaging jaw 22 which, in addition to gripping the rail base, engages the rear face of the yoke. The other end is bent 105 downwardly and outwardly to provide a shoulder 23 adapted to bear against the edge of the rail base and a flange 24 adapted to be secured to the upper surface of the tie 19 by spikes 25. The jaw portion 22 of the 110

fastening member is preferably given a permanent set at an angle to the body portion, so that the fastening member will be tensioned when the device is in its applied position, thereby maintaining a spring grip on the rail base so as to prevent rattling or displacement of the device.

In applying the anchor to the rail, the jaw end 14 of the yoke is hooked over one edge of the rail base and the yoke is then moved in the direction of its length transversely of the rail until the jaw portion 13 clears the opposite edge of the rail base. The yoke may then be moved in a reverse direction until the shoulder 21 of the jaw 14 engages the vertical edge of the rail base. The wedge member 11 may then be positioned under the rail base with its flange 17 against the tie 19, and the yoke member 20 forced upon the tapered portion 18 of the wedge by driving the yoke longitudinally on the rail. When the members of the anchor are in their operative positions, any forward creeping movement of the rail, that is to say, in a direction from the yoke 10 toward the tie 19, will tend to increase the wedging engagement of the wedge 11 between the under surface of the rail base and the body portion of the yoke 10, thereby increasing the grip of the jaws 13, 14, on the upper surfaces of the rail base.

Any tendency which the yoke member may have to back off the wedge (such tendency being present particularly during a rearward creeping movement of the rail when the flange 17 of the wedge is embedded in the ballast of the road-bed), will be resisted by the fastening members 12, 12'.

I claim:

- 40 1. A rail anchor comprising a rail base embracing member, a tie-abutting member formed with a tapered portion adapted to be wedged between the rail base and said embracing member, and means for maintaining said tie abutting member and said rail base embracing member in wedging engagement with each other comprising a resilient jaw member adapted to fit over one edge of the rail base and engage said rail base embracing member.
- 45 2. A rail anchor comprising a rail base embracing member, a wedge member provided with a tie abutment and adapted to be wedged between said rail base and said embracing member, and means for locking said wedge and embracing members in their wedging engagement with each other comprising a bar fixed to a cross-tie and engaging said rail base embracing member.
- 50 3. A rail anchor comprising a rail base embracing yoke, a wedge member provided with a tie-abutment and adapted to be wedged between the rail base and said yoke, and means for locking said wedge and yoke members in their wedging engagement with

each other comprising a bar fixed to the cross-tie and engaging said yoke member.

4. A rail anchor comprising a yoke member provided with jaws for engaging opposite edges of a rail base, a wedge member provided with a tie abutment and adapted to be forced between said yoke and the under surface of said rail base to effect a gripping contact of said jaws with the rail, and means for preventing said yoke backing off said wedge comprising a locking member adapted to be secured to a tie and formed with a jaw to fit over one edge of said rail base and engage with said yoke.

5. A rail anchor comprising a yoke member provided with jaws for engaging opposite edges of a rail base, a wedge member provided with a tie abutment and adapted to be forced between said yoke and the under surface of said rail base to effect a gripping contact of said jaws with the rail, and means for preventing said yoke backing off said wedge comprising a fastening member adapted to be secured to a tie and formed with a jaw to fit over one edge of said rail base and engage with said yoke; said fastening member being formed so as to be tensioned when in its applied position.

6. A rail anchor comprising a yoke provided with jaws for engaging opposite edges of a rail base, a wedge provided with a tie abutment and adapted to be forced between said yoke and the under surface of said rail base to effect a gripping contact between said jaws and the rail, and means for preventing the yoke backing off said wedge comprising a locking member adapted to be secured to a tie and formed with a jaw to fit over one edge of said rail base and engage with said yoke; the jaw portion of said locking member being arranged at an angle to the body thereof whereby said member is tensioned when it is in its operative position so as to effect a spring grip of said jaw portion on the rail.

7. A rail anchor comprising a yoke provided with jaws for engaging opposite edges of the rail base, a wedge provided with a tie abutment and adapted to be forced between said yoke and the under surface of said rail base to effect a gripping contact between said jaws and the rail, and means for preventing the yoke backing off said wedge comprising locking members secured to a tie on opposite sides of said rail, and formed with jaws to fit over the opposite edges of said rail base and engage with said yoke; the jaw portions of said locking members being arranged at an angle to the body of said members whereby they are tensioned when in their operative position so as to affect a spring grip of said jaw portions on the rail base.
